UNITED STATES PATENT OFFICE

2,403,702

MECHANICAL FLASH LAMP

Robert Alexis Adams, Brawley, Calif.

Application April 4, 1944, Serial No. 529,464

3 Claims. (Cl. 240—1)

1

This invention relates to new and useful improvements in mechanical illumination.

A principal object of the invention is to provide a means for flashing light through mechanical expediency, thus doing away with the use of batteries and providing a device which can be used as a distress signal by seamen and others, or for any other desired signal use.

Another important object of the invention is to provide a mechanical device of the character stated which will be positive acting and not susceptible to the ready development of defects.

Other objects and advantages of the invention will become apparent to the reader of the following description.

In the drawings—

Figure 1 represents a front elevational view of the device.

Figure 2 is a side elevational view.

Figure 3 is a rear elevational view.

Figure 4 is a vertical sectional view taken on the line 4—4 of Figure 3.

Figure 5 is a fragmentary detailed sectional view taken substantially on the line 5—5 of Figure 1.

Figure 6 is a section taken on the line 6—6 of Figure 1.

Figure 7 is a section taken on the line 7—7 of Figure 1.

Figure 8 is a fragmentary detailed sectional view showing the latch means.

Referring to the drawings wherein like numerals designate like parts, it can be seen that the numeral 5 denotes a concavo-convex-shaped reflector having a circumferential row of equally spaced slots 6 for receiving serrated wheels 7 carried by a flexible shaft 8, this shaft extending through conduit sections 9 which extend from one slot 6 to the next, as clearly shown in Figure 2. Aligned with each slot 6 is a barrel 10 suitably secured to the outer side of the reflector 5, this barrel having a bore therethrough, one end of which receives a flint 11 while the other end has an adjusting screw 12 feedable therein for adjusting the flint 11 through the medium of a compression spring 13 interposed between the flint and said adjusting screw 12.

A hollow handle 14 depends from the reflector 5 and into this extends the flexible shaft 8 (see Figure 1).

A spring containing cylindrical case 15 extends into the lower end of the handle 14, the lower end having a collar 16 of some resilient material such as rubber to permit ready grasping and rotation of the case 15, this lower portion

2

depending below the lower end of the handle 14. Located within the case 15 is a coiled band spring 17, one end of which is secured to the case 15 while its opposite end is secured to a vertical rigid shaft 18. In the upper end of the case 15 is a spider 19 carrying a bearing 20 for the upper portion of the rigid shaft 18. Slanting teeth 21 are provided at the upper edge of the case 15 and are adapted to be engaged by a beveled spring-pressed tooth 22.

A ratchet wheel 23 is provided on the upper end portion of the rigid shaft 18 and a flexible shaft 8 connects with this ratchet wheel 23 and the rigid shaft 18 as at 24, this representing a suitable form of coupling for the flexible shaft.

Figure 8 shows a latch structure for the ratchet wheel 23 and this consists of a push button 25 operative through an opening 26 in the handle 14, the inner end of this button being pivotally connected as at 27 to one end of a rocker 28, the lower end of which carries a tooth 29 engageable with the teeth of the ratchet wheel 23, it being seen in Figure 8, that a spring 30 is employed for normally urging the tooth 29 into engaged position with the ratchet wheel 23.

It can now be seen, that the device is set by winding the spring 17, this through the operation of rotating the spring case 15. The latch means shown in Figure 8 will hold the spring until such time as flashlight is desired. Then, the button 25 is pushed inwardly and this releases the tooth 29 from the ratchet wheel 23, thus releasing the spring so that shafts 18 and 8 are rotated. The corrugated wheel 7 in rotating and striking the flint 11 will produce multiple sparks which dashing inwardly of the reflector will produce quite a brilliant light.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A flashlight comprising a reflector, a plurality of roughened wheels, a plurality of spark producing elements and means for urging the elements against the wheels, and releasable spring means for rotating the wheels, said wheels being mounted upon the reflector, a handle for the reflector, said releasable spring means being located in the handle, and a flexible shaft extending from the releasable spring means to the wheels.

2. A flashlight comprising a reflector, a handle for the reflector, a plurality of roughened wheels mounted on the reflector, said reflector having openings through which the wheels project, spark producing elements mounted in contact with the wheels, a flexible shaft circumscribing the reflector and having a driving connection with the wheels, and means in the handle for rotating the flexible shaft.

3. A flashlight comprising a reflector, a handle 10 releasing the spring to rotate the flexible shaft for the reflector, a plurality of roughened wheels

mounted on the reflector, said reflector having openings through which the wheels project, spark producing elements mounted in contact with the wheels, a flexible shaft circumscribing the reflector and having a driving connection with the wheels, and means in the handle for rotating the flexible shaft, said means in the handle consisting of a spring, means for winding and holding the spring, and means on the handle for releasing the spring to rotate the flexible shaft.

ROBERT ALEXIS ADAMS.
